United States Patent Office

Des. 177,620
Patented May 8, 1956

177,620

RECLINING CHAIR

Morris Futorian, Glencoe, Ill.

Application April 19, 1955, Serial No. 35,572

Term of patent 3½ years

(Cl. D15—11)

Des. 177,620

PAGE 2

Fig. 3.

Fig. 1 is a side perspective view of a reclining chair embodying my new design, the back and foot rest elements being in an extended position;

Fig. 2 is a front perspective view of the reclining chair; and

Fig. 3 is a rear perspective view thereof.

I claim:

The ornamental design for a reclining chair, as shown and described.
